[57] ABSTRACT

Bituminous sand is contacted with ozone to render the bitumen partly water soluble and to create surface active agents in situ which promote oil-in-water emulsification and increase the water wettability of the sand. Bitumen can then be removed and recovered from the sand formation by flushing it with an aqueous solution.

PROCESS FOR DEVELOPING INTERWELL COMMUNICATION IN A TAR SAND

CROSS-REFERENCE TO RELATED APPLICATION

This application is a continuation-in-part of my application Ser. No. 79,346, filed Aug. 10, 1970 now U.S. Pat. No. 3,706,341.

BACKGROUND OF THE INVENTION

This invention relates to oxidizing bitumen present in tar sand to render the bitumen water-soluble and more susceptible to oil in water feet so that it can be separated from the sand and recovered.

Large portions of the Athabasca tar sand deposit in Canada are buried beneath overburden, which can be as much as a thousand feet in thickness. Because of the over-burden, the bitumen must be separated in situ from the sand if one is to recover the bitumen for oil production on a commercial scale. A number of in situ techniques are presently being investigated. One such approach involves injecting steam into the formation through an injection well. The steam renders the bitumen less viscous and it forms an oil-in-water emulsion with the steam condensate. This emulsion can be forced by a pressure gradient to migrate to a nearby production well, from which it is recovered.

A problem associated with the aforementioned steam injection process is that of successfully providing through the tar sand formation a permeable, competent communications path or zone connecting the injection and production wells. This path, when developed, functions to provide a means for introducing the steam into the formation across a broad area on a continuous basis and for simultaneously removing the emulsion which is formed. In the past, the path has been developed by: (1) hydraulically fracturing the formation to form a fracture system connecting the production and injection wells; and (2) then injecting steam into the fracture system to gradually emulsify the surrounding bitumen — the emulsion is removed to develop a thick permeable path. The procedure is difficult to practice because the steam pressure which is required is so high that vertical fracturing frequently occurs.

In my co-pending application Ser. No. 66,545, filed Aug. 24, 1970, now abandoned, I disclose a low-pressure method for developing a hot, competent, permeable communications path connecting the wells, before pure steam is introduced to the formation. This method comprises introducing an aqueous solution at formation temperature and containing sodium hydroxide (in amount less than 1.0 percent by weight) and a non-ionic surfactant (e.g., between 0.1 and 5 percent by weight of an octylphenoxy polyethylene oxyethanol in which the octyl group is branched and which contains about 5 moles of ethylene oxide) into the fracture system. The solution slowly emulsifies bitumen adjacent to the path. The emulsion is slowly pumped at a relatively low pressure to the production well for removal. The temperature of the solution is gradually increased at a rate such that all the bitumen entering the flow path is emulsified. As the temperature of the solution is increased, the concentrations of the caustic and surfactant are gradually decreased. Eventually only pure, hot steam is injected. By practising this technique, the danger of vertical fracturing is minimized.

SUMMARY OF THE INVENTION

The present invention is concerned with improving the technique of developing an interwell communications path, prior to injecting steam only. More specifically, I have found that, when bituminous sand is contacted with ozone and is subsequently flushed with water or an aqueous solution containing caustic and a non-ionic surfactant, some bitumen separates from the sand and is carried away with the flushing solution, thereby gradually developing a permeable communications path through the formation. Without wishing to be bound by any technical explanation of this process, I believe that the ozone oxidizes bitumen to form acidic groups; the product is characterized by decreased bitumen-water interfacial tension, increased wettability of the sand, increased solubility of the bitumen in water and increased ease of oil-in-water emulsion formation. If a caustic solution is used to flush the formation, I believe the caustic reacts with acidic groups in the bitumen to form organic salts which increase the hydrophilic character of the bitumen, thus rendering an increased amount water soluble and a further fraction surface active which aids the bitumen to combine and move with the water.

According to one embodiment of the invention, the method comprises: (1) injecting ozone into tar sand to contact bitumen and react with it to form a product which is relatively water soluble in comparison to unreacted bitumen; and (2) flushing the tar sand with a solution which separates and removes reacted bitumen from the sand — This solution may be water, water containing caustic, or water containing caustic and a non-ionic surfactant.

DESCRIPTION OF THE PREFERRED EMBODIMENT

The following examples illustrate the invention:

Example I

This example illustrates the use of ozone as a means for establishing a bitumen-depleted zone within tar sand.

A 1 1/2 × 18 inch glass column was packed with 800 grams of Athabasca tar sand. Oxygen containing 6 - 7 percent by volume ozone was passed through the tube for 2 days at 170 millimetres per minute. The experiment was carried out at room temperature.

During this period, the colour of the sample changed from black to gray as many white, clear sand grains appeared.

At the end of the two day period, the column was eluted with water. The collected eluent was dark brown in colour and foamed when shaken lightly. It was evaporated to dryness and the solid product analyzed as follows:

TABLE I

Constituent	% by weight
carbon	41.6
hydrogen	5.0
oxygen	37.3
nitrogen	1.3
sulphur	6.6
drying loss	8.2

A portion of the water-extracted ozonized tar sand was divided into three 50 gram parts A, B and C. These parts were each placed in a tube.

Part A was saturated at 40° F with water containing 0.2 percent by weight sodium hydroxide and 0.4 percent by weight Triton X-45 (a trade mark identifying an octylphenoxy polyethylene oxyethanol manufacture by Rohm and Haas). Within 30 minutes the solution turned dark brown, indicating very rapid emulsification of the bitumen.

Part B was saturated at 40° with water containing 0.2 percent by weight sodium hydroxide. No change in the colour of the solution had occurred after 2 days.

Part C was saturated at 40° with water containing 0.4 percent by weight Triton X-45. Some darkening of this solution occurred in 30 minutes.

A fourth part D of the ozonized tar sand was stirred with water at room temperature under a microscope. The sand and bitumen separated and the bitumen formed globules in the water phase. When non-ozonized tar sand was subjected to the same test, nothing happened.

From these results it will be noted that:

- a. treatment of tar sand with ozone converts some bitumen to a water-soluble form;
- b. some of the ozonized bitumen has surface active characteristics; and
- c. ozonized tar sand is more amenable to spontaneous emulsification with an aqueous solution of sodium hydroxide and non-ionic surfactant than is otherwise the case.

Example II

This example illustrates that ozone is effective at formation temperature.

A horizontal 3-foot × 2-inch column was tightly packed with 5.2 pounds of Athabasca tar sand. A $\frac{1}{8}$ inch diameter path of 20 - 40 mesh round sand was incorporated in the tar sand along the bottom of the column.

Oxygen containing 5-6 percent by volume ozone was passed through the column for 61 hours. The exit gas contained only 1 percent ozone.

A 50-gram sample of the ozonized tar sand was extracted with 500 millilitres of water to yield a dark-brown solution which foamed when shaken lightly. Evaporation of the solution to dryness yielded 0.237 grams of solid material. This material analyzed as follows:

Table II

Component	% by weight
carbon	28.7
hydrogen	3.7
oxygen	51.3
nitrogen	1.3
sulphur	8.2
drying loss	6.8

This surface tension of a solution of this material in water was as follows:

TABLE III

Concentration p.p.m.	Surface tension Pynes./cm.
250	69.6
500	62.5
1000	60
2000	53.7

A second 50 gram sample was extracted with 1.1 litres of water. The solution required 41.4 cubic centimetres of 0.1 sodium hydroxide to neutralize it. This test indicated the formation of acid groups due to reaction between the ozone and bitumen.

In sampling the tube, samples were taken from 4 equal-length sections along the tube, designated A, B, C, and D, starting from the ozone-inlet end. The bitumen was extracted from each of these samples and from a sample of unozone tar sand (designated sample 0) using toluene reflux. Elemental analyses of these bitumen samples and their molecular weights are shown in Table III. Standard S.A.R.A. analyses were conducted on each of the samples; thus dividing each of them into asphaltenes, resin I, resin II, saturates, and aromatics. The results of this analysis are given in Table IV. Elemental analyses and molecular weights were carried out on each of the sub-samples. The results are shown in Table V. These analyses show that in general ozonolysis was limited to the asphaltene and resin fractions of the bitumen and that it resulted in a lower molecular weight and a decrease in the sulphur content. The saturates and aromatics were little affected; these fractions, however, are of low molecular weight and viscosity. Thus ozonolysis is attacking that part of the bitumen which is of highest molecular weight and viscosity, and converting it into water soluble or more hydrophylic material.

Example III

A second 3-foot by 2-inch horizontal tube was packed as before, and ozone (6 percent in O_2) was passed through for 7 days (80 percent of the ozone was still being absorbed by the cell after 7 days). Distilled water (20 ml/hr) and ozone (6 percent in O_2) were then passed through the tube for 6 days. Examination of the cell disclosed areas around the sand path and extending out around the surface of the cell which had been largely depleted of bitumen, leaving clean white sand. The initial effluent from the cell (first day's effluent after commencing water injection) was an amber color (pH, 1.35) and contained about 6 percent water-soluble organic material. The surface tension of this material as a function of concentration together with the surface tension of this material after neutralization with NaOH is shown in Table VII.

TABLE VII

Concen- tration p.p.m.	Surface Tension Neutralized Form	Surface Tension Acid Form
4000	61	56
8000	59	53.5
16,000	48	49.5
21,000	47	48
26,000	.....	45.8
32,000	48	45.3
42,000	—	45.8
64,000	—	42.5

Approximately 9.5 percent of the bitumen originally in the cell was removed during the 6 days of water injection.

The test cell was reassembled and a solution of 0.2

percent NaOH was passed through the cell for 14 days (20 cc/hour). An additional 8.7 percent of the bitumen in the cell was removed during this period. Most of the cell effluent which was collected during the first 6 days of water injection was neutralized to pH7, and this material was recycled through the cell six times. This procedure removed a further 2 percent of the bitumen from the cell, for a total bitumen recovery of 20.2 percent. When the cell was opened and the tar sands examined it became evident that the whole cross section of the tube had been affected to some extent by the combination of ozonolysis, distilled-water flush, NaOH-solution flush, and neutralized-effluent recycle, but in some areas, notably near the original sand path and extending around the glass surface, the bitumen had been extensively removed.

These results indicate that ozone readily reacts with bitumen at formation temperatures (40° F) to form water-soluble highly-oxygenated materials which have surface active properties in both acid form and as neutralized salts. Passing of water through an ozonized formation of tar sands results in removal of part of the bitumen; in some areas this removal is extensive while in other areas it is minor. When 0.2 percent sodium hydroxide solution is passed through such a bed, more bitumen is removed and the highly-depleted areas are extended. Recycling the cell effluents, which contain surface active agents which were formed insitu, results in further bitumen removal.

What is claimed is:

1. A method for in situ treatment of bitumen contained in a tar sand formation to convert the bitumen to a partly water-soluble state, which comprises:
contacting bitumen in the formation with ozone whereby the bitumen and ozone react to form a product having greater water solubility than non-reacted bitumen.
2. A method for converting bitumen contained in a tar sand formation to a partly water-soluble state and emulsifying the product whereby it may be moved through the formation, which comprises:
contacting bitumen in the formation with ozone whereby the bitumen and ozone react to form a product having greater water solubility than non-reacted bitumen; and
contacting the product with water to emulsify it.
3. The method as set forth in claim 2 wherein:
the product is contacted with water containing sodium hydroxide.
